UNITED STATES PATENT OFFICE.

JAMES T. SMITH, OF MALDEN, MASSACHUSETTS.

COMBINED CALENDAR AND CONTAINER.

Application filed May 10, 1928. Serial No. 276,748.

This invention relates to advertising novelties and has particular reference to a combined yearly calendar and a container adapted for use as a humidor to hold a quantity of cigars, the advertisement for which is borne by the device, or for other purposes.

One of the objects of this invention is the provision of a device embodying a yearly calendar wherein the days of the month are arranged in weekly groups on a fixed support and the days of the week and the months of the year are arranged in successive groups on a movable holder disposed in operative relation with the list of days of the month, the arrangement being such that the holder can be moved each month to position the list of days for the week in correct relation with the table of numbers of the days.

A further object of the invention is the provision of a calendar of the type above set forth wherein the movable holder constitutes a container adapted to hold cigars and the like.

A further object of the invention is the provision of a device of the class described comprising a supporting casing having a ledge on which the table of days of the month is located and having a cylindrical recess at the rear of the ledge in which a cylindrical container bearing the table of days of the week on its outer periphery is rotatably received. The supporting casing is provided with an aperture above the ledge through which the table of days for one month only of the calendar is visible.

A further object of the invention is the provision of a device of the type described wherein a part of the wall of the supporting casing providing the cylindrical recess is removable and can be removed from the body of the casing and replaced by another similar portion. The detachable portions are adapted to bear different advertisements so that the devices can be changed to advertise different goods at small expense.

A further object is generally to improve the construction of combined calendars and containers.

Fig. 1 is a perspective view of the invention.

Fig. 2 is a section taken along line 2—2 of Fig. 1.

Fig. 3 is a vertical sectional elevation taken along line 3—3 of Fig. 1.

Fig. 4 is a plan view of the container of Fig. 1.

Fig. 5 is a perspective view illustrating a modified form of the invention.

The device embodying the invention comprises a casing formed of a flat metal sheet 10 which has a vertically upstanding section 12 and constituting one of the supports of the device. The sheet is reflexed above said support to provide a substantially flat horizontal shelf 14 that can serve as a holder for pens, pencils, and the like. Beyond the shelf the sheet is reflexed upwardly into semi-circular form as at 16 and is then reflexed backwardly upon itself to provide a sloping or upwardly inclined flat ledge 18. The sheet at the top of the ledge is reflexed sharply upon itself and downwardly to form a semi-cylindrical section 20 which comprises approximately one-half of an open ended cylindrical or tubular casing 22. A second semi-cylindrical sheet 24 is connected with the end of the sheet 10 to cooperate with the semi-cylindrical section 20 thereof to complete the tubular casing.

The sheets 24 and 10 are connected detachably together by a loosely interlocking seam 26 which permits the sheet 24 to be detached from the cooperating sheet 10 by an axial sliding movement thereof as illustrated in the dotted lines in Fig. 1. The top edge 28 of the sheet 24 is terminated in spaced relation with the top edge of the ledge 18 whereby to provide a window 30 above or at the rear of said ledge.

A container 32 is received within said tubular casing. Said container comprises a hollow cylindrical body of sheet metal which is open at both ends and the ends are closed by the removable caps 34. The container here shown is adapted to hold a number of cigars and the caps preferably are provided with an absorbent material 36 held in place by a perforated plate 38, which material is adapted to contain a liquid that will maintain a humid atmosphere in the container. The cylindrical wall of the container is provided at its opposite ends with the peripherally continuous outstanding beads 40, which beads are located within the edges of the cylindrical enclosing casing and bear thereagainst and form runners on which the container can be rotated within the casing without frictional engagement between the container and the cylindrical wall of the casing.

The cylindrical wall of the container, between the beads 40, bears a printed sheet 42 which contains a plurality of successive horizontal columns 44, each containing a horizontal row 46 of the days of the month together with the name of the month. The ledge 18 is provided with a sheet 48 bearing the numbers of the days of the month in vertical rows 50. The container is located 10 within the tubular casing with the horizontal day column 46 exposed through the opening or window 30 above and in line with the columns 50, thus to constitute a calendar for one particular month of the year. By rotating the container 32 any particular month column 44 can be brought into register with the table 46, thus to change the calendar for the particular month desired.

The metal sheets 10 and 24 are somewhat 20 resilient and serve to hold the container 32 frictionally in any adjusted position. The semi-cylindrical sheet 24 is adapted to bear upon its outer face some appropriate advertisement which may be an advertisement of 25 the cigars contained in the container. Said section 24 can be removed and replaced by another section bearing a different advertisement if it is desired.

In the modification illustrated in Fig. 5, 30 the entire casing is made from a single sheet of material formed into shape with the end 10^a of the sheet secured by rivets 52 to the intermediate body of the sheet above the ledge 18^a. In this modification the window 35 30^a is located within the opposite ends of the casing.

The construction can be otherwise modified without departing from the spirit of the invention.

I claim:

1. A combined calendar and container comprising a horizontal tubular casing having a window therein and a ledge at said window, said ledge having calendar insignia thereon consisting of horizontal rows of consecutive members from the number one to the number thirty-one, and a cylindrical container rotatable in said tubular casing having calendar insignia on the periphery thereof which are visible through said window and cooperate with the insignia on said ledge to provide a changeable monthly calendar, the calendar insignia of said roll consisting of horizontal lines containing the consecutive days of the week, and other lines containing the names of the months, a day and also a month line being exposed at the same time through said window.

2. A combined calendar and container 60 comprising a horizontal tubular casing having a window therein and a ledge at said window, said ledge having calendar insignia thereon, a foot depending below said ledge, said foot and the bottom of said tubular casing constituting supporting means for the

calendar, and a cylindrical container rotatable in said tubular casing having calendar insignia on the periphery thereof which are visible through said window and cooperate with the insignia on said ledge to provide a 70 changeable monthly calendar, said container having a cap which is removable from the end of the container to provide access to the interior thereof.

3. A combined calendar and container 75 comprising a horizontal tubular casing open at each end and having a window therein and a ledge at said window, said ledge having calendar insignia thereon, a foot depending below said ledge, said foot and the bottom of said tubular casing constituting supporting means for the calendar, and a cylindrical container rotatable in said tubular casing having calendar insignia on the periphery thereof which are visible through 80 said window and cooperate with the insignia on said ledge to provide a changeable monthly calendar, said container having a cap which is removable from the end of the container to provide access to the interior 85 thereof, said container being removable from its aforesaid relation from either open end of said tubular casing.

4. A combined calendar and container 90 comprising a tubular casing having a window therein and a ledge at one side and a free resilient wall at the opposite side of said window, said ledge having calendar insignia thereon, and a cylindrical container 100 rotatable in said tubular casing having calendar insignia on the periphery thereof which are visible through said window and cooperate with the insignia on said ledge to provide a changeable monthly calendar, the free resilient wall of said tubular casing 105 having resilient frictional engagement with said container.

5. A device of the class described comprising a casing formed of sheet material reflexed to provide a tubular section having a 110 window in the periphery and a ledge at the window, and a supporting foot under the ledge and a container received rotatably and removably within said tubular section with a portion of its periphery exposed through 115 said window.

6. A combined calendar and container 120 comprising a tubular casing having a window therein and a ledge at said window, calendar insignia borne by said ledge, a cylindrical container having a removable end cap rotatably disposed within said tubular casing and having calendar insignia which are visible through said window and cooperate with the insignia borne by said 125 ledge, said container having at its ends circumferential beads which outstand beyond the calendar insignia on the container and bear upon the inner face of said tubular casing and protect said calendar insignia 130

against rubbing engagement with said casing.

7. A combined calendar and container comprising a tubular casing having a two-section wall one of which sections has a detachable connection with the other section, said tubular casing having a window and a ledge at said window, said ledge having calendar insignia thereon, and a cylindrical container rotatably received within said tubular casing having calendar insignia on its outer periphery which are exposed through said window and cooperate with the insignia borne by said ledge to provide a changeable 10 monthly calendar.

8. A combined calendar and container composed of sheet metal reflexed to provide a ledge and a tubular casing, the portion of said sheet forming said tubular casing being terminated in spaced relation with an edge of said ledge, whereby to provide said tubular casing with a window, calendar insignia carried by said ledge, and a cylindrical container rotatably received within

said tubular casing and having other 25 calendar insignia thereon which are exposed through said window to cooperate with the calendar insignia of said ledge to provide a changeable calendar.

9. A combined calendar and container comprising a holder composed of sheet metal reflexed to form a tubular casing, a ledge on said casing, and a supporting foot beneath said ledge, the portion of said sheet forming said tubular casing being terminated in 30 spaced relation with the ledge to provide a window, said ledge having calendar insignia thereon, and a cylindrical casing having a removable end cap rotatably received within said tubular casing having calendar insignia 35 on its outer periphery which are visible through said window and cooperate with the calendar insignia of said ledge to provide a changeable monthly calendar.

In testimony whereof, I have signed my 40 name to this specification.

JAMES T. SMITH.
